UNITED STATES PATENT OFFICE

160,231

COIN HOLDER OR SIMILAR ARTICLE

Raymond R. Ward, Brecksville, Ohio

Application February 15, 1946, Serial No. 126,597

Term of patent 14 years

(Cl. D87—3)

To all whom it may concern:

Be it known that I, Raymond R. Ward, a citizen of the United States, residing at Brecksville, in the county of Cuyahoga and State of Ohio, have invented a new, original, and ornamental Design for a Coin Holder or Similar Article, of which the following is a specification, reference being had to the accompanying drawing, forming a part thereof.

In said drawing, Fig. 1 is a perspective view of a coin holder or similar article showing my design; and Fig. 2 is a similar view, at a different angle.

I claim:

The ornamental design for a coin holder or similar article, substantially as shown.

RAYMOND R. WARD.
